A. J. Sausier.

UNITED STATES PATENT OFFICE.

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE.

AIR CONTROL FOR FURNACES.

Application filed July 13, 1922. Serial No. 574,728.

To all whom it may concern:

Be it known that I, GEORGE L. DANFORTH, Jr., a citizen of the United States, residing at Chicago, in the county of Cook and State of Illinois, have invented certain new and useful Improvements in Air Controls for Furnaces, of which the following is a specification.

This invention relates to air control for furnaces and more particularly to a construction whereby the incoming air may be adequately controlled and directed in furnaces of the open hearth type.

As is well known in the art, an open hearth furnace is double-ended and periodically reversed in operation, the ends serving, alternately, to introduce the air and fuel and to carry off the products of combustion.

Since the products of combustion largely exceed the incoming air and fuel in volume, the ports must be designed largely with regard to the requirements of the products of combustion rather than those of the incoming air and fuel. On the other hand, efficient furnace operation requires that the air and fuel be intermixed to form a relatively short, hot flame properly controlled and directed toward the bath of metal in the furnace. In the endeavor to take care of these two conflicting requirements, certain furnaces have been designed with additional passages which serve on the outgoing end to aid in carrying off the products of combustion and which are closed off on the incoming end by means of dampers. In such constructions, the damper guides and damper rigging complicate the furnace design and operation, and since the damper and guides must be water-cooled, certain heat losses result.

It is an object of the present invention to provide means adapted to produce an auxiliary fluid flow in supplemental passages whereby flow of incoming air through such passages is prevented.

It is a further object to provide auxiliary passages leading to the supplemental passages, the auxiliary passages being adapted to by-pass a portion of the fluid and the introduction of the by-passed fluid into the supplemental passages causing an auxiliary flow relative to said supplemental passages such as to prevent the main body of fluid

from passing into the supplemental passages.

It is a further object to provide a construction of this character which is simple in design and which may be readily applied to existing installations without material alteration therein.

Other and further objects will appear as the description proceeds.

I have illustrated certain preferred embodiments of my invention in the accompanying drawings, in which—

Figure 1 is a vertical, longitudinal section of one end of an open hearth furnace equipped with my invention;

Figure 2 is a transverse section taken on line 2—2 of Figure 1;

Figure 3 is a horizontal section taken on line 3—3 of Figure 1;

Figure 4 is a view similar to Figure 1 showing a modified form of construction;

Figure 5 is a transverse section taken on line 5—5 of Figure 4; and

Figure 6 is a horizontal section taken on line 6—6 of Figure 4.

Referring first to the form of construction shown in Figures 1 to 3, the furnace shown comprises the hearth 8 and the central port 9 through which may be introduced the incoming air and fuel. The nozzle 10 is shown introduced through the rear wall 11 of the furnace into the port 9, the nozzle being adapted to discharge liquid or gaseous fuel. The trench 60 across the port 9 receives the ends of pipes 61 which may be used to introduce gaseous fuels such as natural or coke oven gases. The uptake 12 leads from the slag pocket 13 to the rear end of the port 9. The supplemental uptake passages 14 and 14' are located upon either side of the uptake 12 and connect the slag pocket 13 with the supplemental ports 15 and 15' which lead into the furnace chamber upon either side of the central port 9.

As best shown in Figure 2, the passage 17 leads into the slag pocket, the passage connecting the slag pocket 13 with any usual type of regenerators (not shown). The auxiliary passage 16 leads from passage 17 to a fan-shaped port 18 directed downwardly and transversely of the lower end of the supplemental uptake 14. The pipe 19 is introduced into the passage 16 and is

adapted to carry compressed fluid such as air or steam. The auxiliary passage 20 leads from the passage 17 to the fan-shaped discharge opening 21 upon the opposite side of the slag pocket 13. This opening 21 discharges downwardly and across the lower end of the supplemental uptake 14'. The pipe 22 is directed axially toward the opening 21 and is adapted to conduct compressed fluid thereto.

The auxiliary passage 23 leads from the opening 24 up the lower end of uptake 14 to the discharge pipe 25 which is directed downwardly in the uptake 14. The pipe 26 is directed axially into the pipe 25 and is adapted to introduce compressed fluid thereto. Similarly, the auxiliary passage 27 leads from the opening 28 at the lower end of uptake 14' to the pipe 29 which discharges downwardly into the upper portion of the uptake 14'. The pipe 30 is directed axially into the pipe 29 and is adapted to introduce compressed fluid thereto.

It will be observed that the division wall 31 between the uptake 14 and the uptake 12 is shorter than the similar wall 32 between the uptakes 12 and 14'. Also the lower end of the division wall 31 is located above the entrance of the passage 17 into the slag pocket.

Referring now to the form of construction shown in Figures 4 to 6, the furnace comprises the melting chamber 40 into which discharges the main port 41. The uptake 42 leads into the forward portion of the port 41 from the slag pocket 43. Flow through the upper end of the uptake 42 is controlled by the hinged damper 44. The uptake 45 leads into the rear end of the port 41 from the slag pocket 46. The supplemental uptakes 47 and 47' lead from the slag pocket 46 to the supplemental ports 48 and 48'. These ports discharge into the furnace chamber laterally of the main port 41.

The slag pocket 46 is connected by passage 49 to a suitable regenerator (not shown). The auxiliary passage 50 connects the passage 49 with the fan-shaped discharge opening 51 which is directed downwardly and across the lower end of the supplemental uptake 47'. The pipe 52 is directed axially of the opening 51 and is adapted to introduce compressed fluid. The auxiliary passage 53 leads from the passage 49 to the discharge opening 54 directed downwardly and across the lower end of the supplemental downtime 47. The pipe 55 is directed axially of the opening 54 and is adapted to introduce compressed fluid thereto.

It will be noted that the division wall 56 between the uptake 45 and uptake 47 is shorter than the similar division wall 57 between the uptake 45 and the uptake 47'.

Also the lower end of the division wall 56

is located above the entrance of the passage 49 into the slag pocket 46.

In the operation of the type of furnace shown in Figures 1 to 3, upon the incoming end the air which has been preheated in a suitable regenerator is led through passage 17 to the slag pocket 13. From the slag pocket 13, it passes freely up the uptake 12 to the port 9 where it is joined by the fuel introduced through nozzle 10 or through pipes 61 and trench 60. The flow of air from passage 17 passes below the lower end of the division wall 31 and hence largely passes by the opening at the lower end of the auxiliary uptake 14. The lower end of the division wall 32 aids in directing it into the uptake 12.

A portion of the air is drawn through the auxiliary passage 16 and by means of a current of compressed air or steam introduced through pipe 19 is discharged through the fan-shaped opening 18 to form a screen or curtain across the lower end of the uptake 14. A further portion of air is by-passed through passage 20 and is forced through the fan-shaped opening 21 by means of compressed air or steam introduced through pipe 22 and thus forms a screen or curtain across the lower end of uptake 14'.

As an alternative or additional means of preventing flow of incoming air upwardly through the passage 14, a certain amount of air is by-passed through the auxiliary passage 24 and is introduced through pipe 25 into the uptake 14, the flow being caused by compressed fluid introduced through pipe 26. This auxiliary flow in the uptake 14 is in a downward direction and thus aids in preventing an upward flow in the uptake. A similar auxiliary downward flow is introduced in the uptake 14' through pipe 29. On the outgoing end, the compressed fluid passing through pipes 19, 22, 26 and 30 is shut off by any suitable control means and the products of combustion flow down all three uptakes 12, 14 and 14'.

The form of construction shown in Figures 4, 5 and 6 is adapted for use with producer gas or other fuel which is preheated and which will be introduced through slag pocket 43 and uptake 42 into the forward end of port 41. The incoming air will be preheated and will pass from the regenerator through passage 49 to slag pocket 46. The main flow of air will pass by the lower end of wall 56 and will be directed by the lower end of wall 57 into and up the uptake 45.

The lower end of the uptake 47 is screened off by a curtain of air which is drawn through the passage 53 and directed through opening 54 by compressed air or steam introduced through pipe 55. Similarly, the lower end of uptake 47' is covered by a curtain of air discharged through opening 51.

The relative flow of air and fuel in the port 41 may be controlled by the swinging damper 44.

Upon the outgoing end of the furnace, the 5 products of combustion pass through the main port 41 and also the supplemental ports 48 and 48' and thence down the uptakes 45, 47 and 47' to the slag pocket 46. Some portion of these gases also passes through the 10 fuel uptake 42 to the slag pocket 43. From the slag pockets, the heated gases are passed to the regenerators.

It will be apparent that in both forms 15 of construction shown a large area is provided upon the outgoing end whereby the large volume of products of combustion may be adequately discharged from the furnace chamber. On the other hand, upon the incoming end, the incoming air is concentrated 20 through a passage of relatively small area and is so directed in relation to the fuel as to cause proper combustion and the desired short and adequately controlled flame. The construction involves no water-cooled dampers with their consequent heat losses and no 25 moving parts of any kind to complicate the installation.

While I have shown two preferred forms 30 of my invention, it is obviously capable of modification and change to suit varying conditions and furnace constructions. It is my intention to cover all such modifications and changes as come within the scope of the appended claims.

35 I claim:

1. In an open hearth furnace, uptakes entering the furnace ends, and means adapted to introduce an auxiliary fluid flow longitudinally of certain of said uptakes whereby 40 the flow of fluid through the uptakes may be controlled.

2. In an open hearth furnace, uptakes entering the furnace ends, and pipes adapted to introduce an auxiliary fluid flow longitudinally of certain of said uptakes, and means to cause a flow through said pipes whereby the flow of fluid through the uptakes may be controlled.

3. In an open hearth furnace, uptakes 50 entering the furnace ends, and pipes adapted to introduce an auxiliary fluid flow longitudinally of certain of said uptakes, and nozzles for discharging compressed fluid in the pipes to cause a flow through said pipes whereby the flow of fluid through the uptakes may be controlled.

4. In an open hearth furnace, passages entering the furnace ends, pipes entering certain of said passages, and auxiliary passages adapted to by-pass fluid from the main passages and conduct it to the pipes, the ends of the pipes extending into the passages and discharging longitudinally thereof.

5. In an open hearth furnace, passages 65 entering the furnace ends, pipes entering

certain of said passages, auxiliary passages adapted to by-pass fluid from the main passages and conduct it to the pipes, the ends of the pipes extending into the passages and discharging longitudinally thereof, and 70 means adapted to cause a fluid flow through said auxiliary passages.

6. In an open hearth furnace, passages entering the furnace ends, pipes entering certain of said passages, auxiliary passages 75 adapted to by-pass fluid from the main passages and conduct it to the pipes, the ends of the pipes extending into the passages and discharging longitudinally thereof, and nozzles adapted to discharge compressed fluid 80 adapted to cause a fluid flow through said auxiliary passages.

7. In an open hearth furnace, passages entering the furnace ends, and means adapted to introduce an auxiliary fluid flow in 85 certain of said passages in the direction away from said furnace.

8. In an open hearth furnace, passages entering the furnace ends, certain of said 90 passages increasing in size toward the furnace, and means adapted to introduce an auxiliary fluid flow in said passages in the direction away from said furnace.

9. In an open hearth furnace, a slag pocket, passages leading from said slag pocket 95 to the furnace chamber, and means adapted to project fluid to prevent flow from said slag pocket through certain of said passages.

10. In an open hearth furnace, a slag pocket, passages leading from said slag pocket to 100 the furnace chamber, and means serving to introduce an auxiliary fluid flow adapted to prevent flow from said slag pocket through certain of said passages.

11. In an open hearth furnace, a slag pocket, passages leading from said slag pocket to the furnace chamber, and means adapted to prevent flow from said slag pocket through certain of said passages, said means comprising pipes extending into the 110 passages and directed toward the slag pocket, said pipes being adapted to discharge an auxiliary fluid flow.

12. In an open hearth furnace, a slag pocket, passages leading from said slag pocket 115 to the furnace chamber, and means adapted to prevent flow from said slag pocket through certain of said passages, said means comprising pipes extending into the passages and directed toward the slag pocket, auxiliary 120 passages leading to said pipes, and means adapted to cause fluid flow through said auxiliary passages and pipes.

13. In an open hearth furnace, a slag pocket, passages leading from said slag pocket to the furnace chamber, and means adapted to prevent flow from said slag pocket through certain of said passages, said means comprising pipes extending into the 125 passages and directed toward the slag pocket, 130

auxiliary passages leading to said pipes, additional auxiliary passages discharging transversely of said main passages, and means adapted to cause fluid flow through said auxiliary passages and pipes.

14. In an open hearth furnace, a slag pocket, passages leading from said slag pocket to the furnace chamber, and means adapted to prevent flow from said slag pocket through certain of said passages, said means comprising pipes extending into the passages and directed toward the slag pocket, auxiliary passages leading to said pipes, additional auxiliary passages discharging transversely of said main passages, and noz-

zles adapted to discharge compressed fluid to cause fluid flow through said auxiliary passages and pipes.

15. In an open hearth furnace, a slag pocket, uptakes leading from the slag pocket laterally of said uptakes, division walls between said uptakes, the division wall adjacent the lateral passage entrance terminating above said entrance, and the next division wall extending below the upper side of said entrance.

Signed at Chicago, Illinois, this 10th day of July, 1922.

GEORGE L. DANFORTH, JR.
